UNITED STATES PATENT OFFICE

2,144,506

AUTOMOBILE HEATER STRUCTURE

Elbert L. Potter, Buffalo, N. Y., assignor to Houde Engineering Corporation, Buffalo, N. Y., a corporation of New York

Application April 17, 1937, Serial No. 137,413

1 Claim. (Cl. 257—16)

My invention relates to heaters for automotive vehicles and an improved method for installation of the same. The invention concerns particularly heater structures in which the heating element is the exhaust gas from the vehicle engine, with the heat of the gases conducted to the heat conveying element such as air which is conducted to the vehicle to be heated. This type of heater usually is interposed in the exhaust line between the engine exhaust manifold and the muffler.

10 A desirable location for the heater is directly adjacent to the entrance end of the muffler so that the exhaust gases, after traversing the heater, may flow directly into the muffler.

15 An important object of the invention is, therefore, to provide an arrangement in which a section of the exhaust piping in advance of the muffler may be readily removed or sawed out to make way for the heater.

20 A further object is to so construct the heater frame that its one end may be slipped over the entrance end of the muffler body and the other end may be connected with the piping extending from the engine manifold.

25 Referring to the drawing,

Figure 1 shows part of a standard type of automobile muffler and piping extending therefrom which would ordinarily connect the engine exhaust manifold with the muffler, and indicating 30 a portion of the piping to be cut out for accommodating the heater; and

Figure 2 is a side elevation showing the heater structure interposed and to take the place of the cut out piping.

35 On the drawing, I have shown a standard type of muffler 10 comprising a cylindrical body having at its inlet end the header 11 with the inlet neck or nipple 12 extending outwardly therefrom for receiving the end of piping P extending from 40 the engine exhaust manifold. For the purpose of inserting the heater structure H shown in Figure 2, the piping P between the dotted cross lines X and Y in Figure 1, is removed or cut out.

45 The heater shown comprises inlet and outlet header structures designated generally by A and B. The inlet header A comprises the header wall or disk 13 and the conical head frame 14 terminating in a pipe receiving neck or nipple 15, the header wall and frame being secured together at 50 their peripheral portion as by welding.

55 The outlet header structure B is a cylindrical shell or sleeve 16 of suitable sheet metal having the header wall or disk 17 at its inlet end, and this wall may be integral with the shell or in the form of a separate element welded thereto. The

heads 13 and 17 have openings for receiving the ends of the flues 18 which are secured to the walls as by brazing or welding. A small distance inwardly on the header walls 13 and 17, header walls or disks 19 and 20 receive the flues and are secured in the opposite ends of a cylindrical wall or shell 21 to form therewith an air chamber 22 having an inlet nipple 23 and an outlet nipple 24, the inlet nipple being adapted for connection with means for propelling air through the chamber 22, such as a blower, and the outlet nipple 24 being adapted for connection with piping for conducting the heated air to the automobile to be heated. The flues may have spiral elements 25 therein for more uniform distribution of the 10 exhaust gases flowing through the flues and for directing them into more intimate contact with the flue walls around which the air circulates. Fin plates 26 may also be mounted on the flues to distribute the air flow more uniformly around 15 the flues and to afford additional radiation surface so that sufficient heating of the air will be accomplished.

20 A distance outwardly of the flue header 17, the outlet shell 16 is radially expanded to provide an 25 internal shoulder 27, the outer portion 16' of the shell being of an internal diameter so it may be slipped over the end of the body of the muffler 10, with the end of the muffler abutting the shoulder 27. The inlet nipple 15 for the heater 30 is of a diameter to receive the piping P after the section between the lines X and Y of Figure 1 have been removed or cut out of the piping.

35 Preferably, the cut along the line X is made close to the end of the muffler body so that when the heater has been slipped over the muffler body end, the exhaust gases may more readily flow into the muffler through the nipple opening 28, the muffler header walls 11, the heater flue header wall 17, and the surrounding shell 16, then forming 40 a collecting chamber 29 for receiving the exhaust gases from the heater and from which the gases flow through the opening 28 for passage through the muffler.

45 After the heater has been interposed in the exhaust line, its outlet header shell is secured to the muffler as by suitable clamps 30, and the inlet nipple 15 may be secured to the end of the piping P by suitable clamp means 31. When 50 thus interposed in the exhaust line, the heater structure and the muffler are intimately associated, the exhaust gases after leaving the heater flowing directly into the muffler instead of first being required to flow through the piping. The heater will also serve as a primary retarding and 55

muffling means for the exhaust gases whose flow is finally muffled during passage through the muffler structure.

Where the automobile manufacturer does not install a heater as part of the car equipment, he can leave sufficient space in front of the muffler for installation of my improved heater by accessory dealers. The car manufacturer might provide a separate length of piping at the muffler which could be readily removed when it is to be replaced by the heater, or he could leave the piping leading to the muffler of sufficient length so that a section thereof could be cut out for replacement by the heater.

15 I have shown a practical embodiment of the various features of my invention and I do not desire to be limited to the exact construction, arrangement, and operation as shown and described, as changes and modifications may be 20 made without departing from the scope of the invention.

I claim as follows:

In combination, an automobile engine muffler having a cylindrical body with a header at its

inlet end provided with an inlet passageway, an automobile heater comprising inlet and outlet headers with flues extending therebetween and surrounded by walls providing a chamber for the flow of air to be heated before delivery to the automobile, the heater inlet header being adapted for connection with the exhaust pipe from the automobile engine, the heater outlet header being circular and having a cylindrical wall extending therefrom and of the same diameter as the 10 header and expanded to a larger diameter at its outer portion for telescopically receiving the inlet end of the muffler body and to provide an annular internal shoulder for engaging with the muffler end whereby to limit the telescopic engagement 15 of said cylindrical wall with said muffler body to thereby define a collecting chamber of predetermined capacity between the outlet header of the heater and the inlet header of the muffler for the collection and expansion of the gases from 20 the heater flue before flow thereof through the muffler inlet header passageway to the muffler body.

ELBERT L. POTTER.
